UNITED STATES PATENT OFFICE.

HORATIO BARNETT, OF MALVERN, ARKANSAS.

NUT-LOCK.

1,217,686.

Specification of Letters Patent. Patented Feb. 27, 1917.

Application filed August 29, 1916. Serial No. 117,505.

To all whom it may concern:

Be it known that I, HORATIO BARNETT, a citizen of the United States, and a resident of Malvern, in the county of Hot Spring and State of Arkansas, have invented 5 a certain new and useful Improvement in Nut-Locks, of which the following is a specification.

My invention is an improvement in nut locks, and has for its object to provide a simple, inexpensive yet efficient lock of the character specified, and to provide a new and improved form of tool for placing the lock.

15 In the drawings:

Figure 1 is a front view with parts in section, showing the improved lock and the placing tool with the lock in closed position;

20 Fig. 2 is a similar view showing the lock in open position;

Fig. 3 is a section on the line 3—3 of Fig. 1, looking in the direction of the arrows adjacent to the line; and

25 Fig. 4 is a perspective view of the lock attached.

In the present embodiment of the invention, the nut lock is in the form of a split ring 1 of suitable dimensions, the said ring 30 having at each side of the split and at the outer face of the ring, undercut notches or recesses 2, for a purpose to be presently described.

The opening of the ring is of lesser diameter 35 than that of the bolt 3, and the said ring is adapted to fit around the threaded portion of the bolt outside of the nut 4. The interior of the lock is provided with two 40 series of teeth 5, the said series being at opposite sides of the diameter through the split. In the present instance, seven teeth are provided in each series, and while in practice the number may be varied, it is obvious that there should be at least four and 45 not more than seven in the series. Each of the teeth, as shown, is of pyramidal form, and they are so shaped that they will engage the bottom of the groove of the thread and will bite into the material of the bolt when 50 in place on the same.

Each of the teeth has a broad base and while the outer face, that is, the face at the end of the ring is perpendicular to the axis of the ring, the inner face is inclined and 55 concaved, as shown in Fig. 3, so that the

point of each tooth may enter and engage the bottom of the groove.

A tool is provided for placing the ring, the said tool comprising a pair of similar levers 6, each of which is provided at one 60 end with a round lug 7 for entering the notch 2 of the ring, and adjacent to the lug each lever has a cam member 8. The cam members are so arranged that when the grip ends of the levers are swung together the 65 lugs 7 will be gradually forced apart. Each lever is slotted transversely, as indicated at 9, at the cam members, and within the slots 9 is arranged an arc-shaped link 10. Each lever has a transverse pin 11 for pivotally 70 and slidably connecting the link with the lever, and the link is of a length to permit the required movement in placing the lock.

In use the locks are placed in the manner indicated in Figs. 1 and 2. The tool is first 75 engaged with the split ring, as shown in Fig. 1, the lugs 7 engaging the notches 2, and with the grip ends of the levers widely separated, as shown. When so arranged, the nut being in place, the grip ends of the 80 levers are swung toward each other and the split ring will be enlarged or opened as shown in Fig. 2. The ring is now placed about the bolt in the manner indicated in Fig. 3, and the grip ends of the levers are 85 again separated to permit the natural resiliency of the ring to close it on the bolt. The ring is seated close to the outer face of the nut and the teeth of each series will 90 engage in the bottom of the groove and will bite into the metal of the bolt, firmly locking the nut in place. To remove the lock it is only necessary to reverse the operation of placing the lock.

It will be noticed that the series of teeth 95 are separated opposite the split at a clear portion free from teeth. This permits the teeth to engage the thread without damaging or marring the same.

I claim:—

1. A nut lock comprising a split ring having a lesser internal diameter than the bolt it is to engage, and having at the end remote from the nut a plurality of series of inwardly extending teeth adapted to engage the bottom of the groove of the thread, said ring having at each side of the split an external undercut notch for engagement by a placing tool, the series of teeth being at opposite sides of the split and the ring having 105 110

- a clear space free from teeth at the opposite side from the split.
2. A nut lock comprising a split ring having inwardly extending teeth at one end and shaped to engage the bottom of the groove of the thread of the bolt upon which the lock is to be placed, said ring having at each side of the split an external notch for engagement by a tool to open and close the lock, and the tool comprising a pair of levers each having an outwardly extending lug for engaging a notch, and a rounded cam surface adjacent to the lug, said surface coöperating to spread the lugs when the other ends

of the levers are moved toward each other, 15 each lever having a transverse notch at the rounded cam portion, an arc-shaped slotted link extending through the slots, and a pivot pin in connection with the levers and engaging the slot of the link. 20

3. A nut lock comprising a split ring having inwardly extending teeth at one end and shaped to engage the bottom of the groove of the thread of the bolt upon which the lock is to be placed, said ring having at each side 25 of the split an external notch for engagement by a tool to open and close the lock.

HORATIO BARNETT.
